UNITED STATES PATENT OFFICE

HERMAN F. GEWALT, OF MILWAUKEE, WISCONSIN, ASSIGNOR OF ONE-HALF TO
WILFRED J. THUERMANN, OF MILWAUKEE, WISCONSIN

TESTING DEVICE FOR SPRINKLER SYSTEMS

Application filed June 6, 1931. Serial No. 542,490.

This invention appertains to fire-extinguishers and more particularly to automatic fire-extinguishers of the type embodying a plurality of automatic sprinkler heads located at spaced points in a water distributing system and in close proximity to the ceiling of a building.

It has been found that in such automatic fire-extinguisher systems, after the same have been installed for a period of time, that the sprinkler heads are liable to become clogged with sediment, thereby rendering the sprinkler heads inoperative. This makes it necessary to test the sprinkler heads at different stated periods of time, which heretofore has been a difficult and troublesome job.

It is, therefore, one of the primary objects of my invention to provide novel means for independently testing each of the sprinkler heads in close proximity to the water outlet passage of said heads without the necessity of turning off the water supply and without any danger of wetting or flooding the territory adjacent to the sprinkler head being tested.

Another salient object of my invention is the provision of novel means incorporated in the sprinkler head for permitting the testing of each sprinkler head to see if there is a free flow of water in each head, said means embodying a detachable operating handle through which the water from the sprinkler head being tested can flow.

A further object of the invention is the provision of a novel valve incorporated directly in each sprinkler head, or adjacent to each sprinkler head, including a hollow valve stem with a novel elongated operating handle for detachable connection with each hollow valve stem for operating the valve and for receiving the water from the valve stem, the water draining from the hollow handle being caught in a suitable bucket or other receptacle.

A further object of my invention is the provision of novel means carried by the hollow handle for operating the sprinkler carried valve and for engaging the hollow stem valve in a water-tight manner, so that leak-

age of water during the testing operation will be eliminated.

A still further object of my invention is to provide a novel means for testing automatic sprinkler heads of a fire-extinguishing system of the above character, which will be durable and efficient in use, one that will be simple and easy to manufacture, and one which can be incorporated with a conventional fire-extinguishing system at a low cost.

With these and other objects in view, the invention consists in the novel construction, arrangement and formation of parts, as will be hereinafter more specifically described, claimed and illustrated in the accompanying drawings, in which;

Figure 1 is a fragmentary side elevation of a water sprinkler head having my improved testing device incorporated therewith, the removable operating handle for the testing valve being shown connected with the valve and the valve head in its partially opened position, the sprinkler head being particularly designed for receiving my invention;

Figure 2 is a horizontal section taken on the line 2-2 of Figure 1, looking in the direction of the arrows, illustrating the means carried by the removable handle for engaging and operating the valve;

Figure 3 is a detailed horizontal section through the valve taken on the line 3-3 of Figure 1, illustrating the novel formation of the valve;

Figure 4 is a fragmentary side elevation of a fire-extinguishing head, showing my improved testing device incorporated therewith, the view illustrating the use of a fitting for permitting the use of conventional types of sprinkler heads now on the market, the operating handle being shown removed;

Figure 5 is a similar view, illustrating the use of a T-fitting for the conventional type of sprinkler head at the end of a sprinkler line.

Referring to the drawings in detail, wherein similar reference characters designate corresponding parts throughout the several views, the latter "A" generally indicates a sprinkler head constructed in accordance

with my invention, connected by means of an elbow 10 with a branch pipe 11 of a sprinkler system (not shown).

The sprinkler head "A" is of substantially the ordinary character, with the exception that I provide in the body 12 thereof, a lateral extending boss 13 internally threaded. This boss 13 has its interior communicating with the interior of the body 12 in close proximity to the outlet passage of the water for the sprinkler head, so that the sprinkler head can be tested in close proximity to said outlet water passage.

In accordance with my invention, I connect with the boss 13, a valve casing 15, which in the present instance is shown to be of an L-shaped design having a depending vertical portion 16. Arranged within the bore of the valve casing 15 in the vertical portion 16 thereof, is provided an annular valve seat 17. Threaded into the lower end of the vertical portion 16 of the valve casing, is a hollow valve stem 18 carrying on its inner end the valve head 19 for normally fitting upon the seat 17. Inward of the valve head 19, the hollow stem 18 is provided with a diametrically extending passageway 20 for communicating with the interior of the valve casing 15.

In order to provide a water-tight joint around the hollow valve stem 18, I provide any preferred type of packing 21 held in place by a threaded cap or bonnet 22.

Attached to the hollow valve stem below the valve casing 15 is an operating wheel 23, which I have shown embodies a hub 24 and a plurality of radially extending arms. This wheel 23 can be formed on or secured to the hollow valve stem in any preferred way, such as by a set screw 26.

As stated, under normal working conditions, the valve head is threaded into contact with the valve seat 17, so that flow of water through the hollow valve stem is prevented.

In conjunction with the valve, I provide novel detachable means for operating the same end for receiving and guiding the flow of water from the valve. This means embodies an elongated hollow operating handle 30 which can be in the nature of a length of pipe. The extreme upper end of the hollow operating handle has threaded thereon or otherwise secured thereto a rubber or other flexible nipple 31, which is adapted to be forced over the extreme lower end of the hollow valve stem 18 for receiving water therefrom when the valve head is moved off of its seat.

I preferably flare the receiving end of the nipple 31 and taper the outer face of the valve stem so as to assure a snug water-tight connection between these parts.

Secured to the handle 30 below the nipple 31 is a substantially U-shaped operating fork 32. As shown, this fork embodies a

hub 33 fitted on the handle and upstanding spaced parallel arms 34, which extend beyond the upper end of the nipple for engagement with the arms 25 of the operating wheel 23.

When it is desired to test a sprinkler system, the operator takes hold of the handle 30 and goes from one sprinkler head to the other until all of the sprinkler heads have been tested. In testing a sprinkler head, the handle 30 is forced upwardly so as to seat the nipple 31 on the lower end of the hollow valve stem 18 with the arms 34 of the yoke 32, engaging the arms 25 of the operating wheel 23. The handle 30 is turned so as to feed the valve head 19 from off of its seat 17, as shown in Figure 1 of the drawings. If the sprinkler head is in good working condition, in accordance to the flow of water, the water will flow from the sprinkler head into the valve casing 15, past the valve seat 17, through the passageway 20 into the hollow valve stem 18 and thence into the pipe or hollow handle 30.

This water can be caught in a suitable receptacle or other convenient drain. After a sprinkler head has been tested, the operating handle is turned in the opposite direction so as to seat the valve head on its seat 17, after which the operating handle is removed from the valve casing and the operator is then ready to test the next adjacent sprinkler head.

In sprinkler systems all ready installed, it may not be desirable, due to the cost of purchasing entirely new sprinkler heads constructed in accordance with my invention. In such instances I can provide attachments or adaptors, as shown in Figures 4 and 5 to permit the use of the conventional sprinkler heads.

In Figure 4, I have shown a branch sprinkler pipe 35 with an elbow 36 to which is generally connected a sprinkler head 37, which is of conventional construction. In order to permit the use of my testing device, I employ the attachment or adaptor 38. This attachment or adaptor 38 consists of a pipe fitting 39 having a threaded extension 40 at one end for threaded connection with the elbow 36. The opposite end of the fitting is provided with an internally threaded socket 41 for the threaded shank 42 of the conventional sprinkler head 37. Intermediate the ends of the fitting an internally threaded bore 43 is provided for receiving the valve casing 15, which is of the exact same type illustrated in Figure 1.

In Figure 5, I have shown a particular type of attachment or adaptor 45, for use at the end of a sprinkler line 46. This adaptor or attachment comprises a T-shaped fitting 47 having its opposite ends internally threaded for reception of the sprinkler line 46 and the valve casing 15, respectively. The

valve casing 15 is of the exact same type shown in Figure 1 of the drawings. The leg of the T fitting 47 is internally threaded for the reception of the threaded shank 48 of a conventional sprinkler head 49.

It is to be understood that while I have stated my improved device can be applied on each sprinkler head, in actual practice my device need only be placed at spaced points 10 in the sprinkler system, such as at the ends of the line or feeders. Not only does my invention give knowledge that the sprinkler heads are opened, but that the pipes are likewise opened and filled with water. These devices 15 are also useful in the winter season to determine whether or not pipes are frozen in a heated building where such conditions would not normally arise, thereby insuring maximum amount of protection at all times. This 20 device is applicable for testing both dry and wet fire sprinkling system, as is readily appreciated by those skilled in the art.

Due to the flexibility of the nipple 31, it is immaterial whether or not the valve casing 25 15 is exactly straight as the handle can be readily engaged with the stem of the valve, if the same should be on an incline.

From the foregoing description, it can be seen that I have provided an exceptional, 30 simple and novel means for testing the automatic sprinkler heads of a fire-extinguishing system which can be readily incorporated with sprinkling systems.

Changes in detail may be made without departing from the spirit or the scope of this 35 invention, but what I claim as new is:

1. In a device for testing the sprinkler heads of fire-extinguishing systems, a valve for each sprinkler head embodying a casing 40 having a depending vertical portion provided with an internal valve seat, a valve stem threaded into the vertical portion having a longitudinal bore and a diametrically extending passageway communicating with 45 the bore and the interior of the casing, a valve head on the inner end of the stem for engaging the valve seat, an operating member on the valve stem arranged exteriorly of the casing, and a removable hollow operating 50 handle having a nipple for receiving the valve stem and a yoke for engaging the operating member.

2. In a testing device, an automatic sprinkler head having an auxiliary valve casing 55 provided with a liquid passage therethrough, a valve in said casing for controlling the flow of liquid through the passage including a valve head for closing the passage and a hollow stem extending beyond 60 the casing, the stem having a port therein beyond the head for the flow of water into the stem a hollow operating handle for the stem, and a flared nipple on the upper end of the handle for receiving the exposed portion of 65 the stem, said nipple being flexible whereby

the handle can be angularly disposed relative to the stem.

3. In a testing device, an automatic sprinkler head having an auxiliary valve casing provided with a liquid passageway, a valve 70 in said casing for controlling the flow of liquid through the passageway, including a valve head and a hollow stem extending beyond the casing, said stem having a port therein beyond the head for the flow of 75 water into the hollow stem a hollow operating handle for the stem, a flared nipple on the handle for receiving the exposed portion of the stem, said nipple being flexible whereby the handle can be angularly disposed relative 80 to the stem, radially extending arms secured to the exposed portion of the stem, and a U-shaped yoke secured to the handle and straddling the nipple engaging said arms, when the nipple is in engagement with the stem. 85

In testimony that I claim the foregoing I have hereunto set my hand at Milwaukee, in the county of Milwaukee and State of Wisconsin.
